UNITED STATES PATENT OFFICE.

GEORGE A. GREENWOOD, OF WORCESTER, MASSACHUSETTS, ASSIGNOR TO UNDERWOOD TYPEWRITER COMPANY, OF NEW YORK, N. Y., A CORPORATION OF DELAWARE.

TYPEWRITING MACHINE.

Application filed June 23, 1924. Serial No. 721,700.

- This invention relates to typewriting machines, and more particularly to the mechanism used in continuous billing and book-keeping machines, as illustrated in the 5 Wernery and Smith Patent, No. 1,132,055, granted March 16, 1915. The plies of a multiple ply work-web are separated after typing into individual sheets, the web being usually fan-folded.
- 10 A feature of the invention is the provision of an attachment whereby the machine may be used occasionally for continuous billing work, and occasionally for ledger-posting or other single-work-sheet purposes. For this 15 enlargement of the capacity of the machine, there is provided an attachable chute or paper guide for the separate work-sheets, said chute having adjustable side gages. The chute may be attached to the cross-bar of the 20 machine. Upon this bar are supported lateral gages for the fan-fold web; and the chute is held from rocking by suitable means such as lugs upon the chute engaging the edges of the gages.
- 25 Another feature of the invention is the provision of means for guiding the leading ends of the separate sheet up around the platen, in the form of fingers which may be temporarily mounted on the usual web-knife, 30 serving to guide the leading edge of the individual work-sheet up around the platen and under the knife, preventing any interference with it when the machine is used in ledger-posting or other single-sheet-work.
- 35 The web-severing knife remains idly in the machine and is used as a support for the guide-fingers, which are taken off when the machine is to be used for web-work.
- 40 A further feature is in the provision of means whereby the usual web-sheet-length-gage may be detached from the paper-table when the machine is to be used for single-work-sheet purposes, rendering the 45 insertion of single work-sheets more convenient.

Other features and advantages will hereinafter appear.

In the accompanying drawings, 50 Figure 1 is a front elevational view of a platen-carriage as used in a bookkeeping machine, showing the application of the invention, many of the details of the car-

riage being omitted as unnecessary to the present disclosure. 55

Figure 2 is a transverse sectional view, taken on line 2—2 of Figure 1, showing substantially the same parts with a single work-sheet inserted.

Figure 3 is a view similar to Figure 2, 60 but illustrating the ordinary construction of the machine as used for multiple-ply webs, the attachments during such work being disengaged.

Figure 4 is a top plan or edge view of 65 the paper-chute.

Figure 5 is a side elevational view of the same drawn to a larger scale and showing the attaching means.

Figure 6 is a perspective view of the 70 paper-guide finger in detail, illustrating the manner of its attachment to the knife.

The present invention contemplates the use of a bookkeeping machine having the features of a continuous billing machine, 75 such as the well-known Underwood-Hanson type. This machine includes a typewriter mounted over a computer, controlled by the numeral-keys of the typewriter and arranged upon a suitable stand. The typewriter mechanism is omitted in the drawings except such parts as constitute the platen-frame and are necessary to a clear disclosure of the invention; the details of the computer mechanism, briefly indicated 80 herein, are similar to the patent to Richard M. Becker, No. 1,296,354, issued March 4, 1919.

Incorporated in the typewriter is a platen 10 mounted on an axle 11 revoluble in a displaceable or inner platen-frame 12 comprised of end plates 13 mounted on pivots 14 carried on arms extending forwardly and upwardly from the ends of the main platen-frame 15. This frame 15 is comprised of end plates 16 connected by a cross 90 rail 17 at the front provided with rollers (not shown); and supported at the rear by bracket elements 18 slidably engaging on a rail 19 fixed to the typewriter-frame 20.

Brackets (not shown), attached to the 100 typewriter-frame 20 at each side thereof, carry a bar 21 on which may be supported one or more sets of denominational jacks 22 and a housing 23 for each set of such jacks. At the rear of each housing 23 is a casing 105 24 for the usual thrust rods (not shown),

and which extends downwardly to the rear of the computer.

The platen axle 11 is provided at its ends with gears 25 which mesh with broad pinions 26 pivoted on the frame of the carriage 15; the broad pinions 26 also mesh with gears 27 similar to the gears 25, and fixed on the inner ends of stub-shafts 28, journaled in the frame of the carriage or 10 platen-frame 15; and the platen 10 may be rotated by means of a finger-wheel 30 or the usual line-spacing mechanism.

When the webs, indicated in general by the letter A, are to be straightened under 15 the platen to permit the withdrawal of the interleaved carbon-sheets B in the usual manner, the platen 10, in its displaceable frame 12, is swung upwardly about the pivots 14, whereupon the webs are drawn forward 20 a distance determined by means of the usual gage 31, adjustable on a gage-bar 32, mounted centrally on a front paper-table 33 which forms part of the platen-displacing frame 12.

As the displacing frame 12 is not swung about the axis of the broad pinions 26, it will be apparent that the gears 25 will be carried out of mesh with the pinions 26 during the displacing movement, but the 30 gears and pinions are provided with teeth which permit ready re-engagement without opposition.

Projecting rearwardly from the platen-frame 15 are brackets 35 carrying a cross rail 36 which forms the front support for the carbon carriage rails 37. A cross-bar 38, mounted at its ends in the platen end plates 16, carries levers 39 provided with hooks 40 to engage with studs 41 in the 40 inner frame end plates 13 to hold the platen when in operative position and one of the levers 39 has a finger-piece by which the hooks may be disengaged. The bar 38 also acts to support the rear edge of a paper-deflector 42, the front portion of which is curved to extend under the platen and cut out to permit the usual feed-rolls 43 to make contact with the platen.

Another cross-bar 45, having at least one 50 flat face 46, extends lengthwise across the carriage between brackets fixed on the platen-frame 15, and paper-guides 47, of novel construction for guiding the work-webs A, are adjustably mounted upon the bar 45. 55 Each guiding member 47 comprises upstanding arms 48 and 49 connected by a yoke or cross-piece 50, the arms having openings therethrough of a shape to conform with the supporting bar 45. The arms 48 and 49 and connecting yoke elements 50 are bifurcated, as at 51, below the openings, the arrangement being such that the arms resiliently grip the supporting bar 45, and 60 yieldably resist movement of the guides 47 along the bar. The flat portion of the sup-

porting bar and corresponding shape of the openings in the guides prevent turning of the guides upon the bar maintaining them erect.

Also mountable on the bar 45 is a paper-chute 52 composed of a pair of plates 53 and 54 respectively, the lower portions of each plate being inclined downward with respect to the main portions, and each plate is provided with a right angular upstanding flange 55 having outstanding projections 56 suited to engage against the front edges of the guide elements 48. Formed in the plate 53 adjacent its lower edge is an elongated slot 57 and operable therein is a rivet 58 so fixed in the upper plate 54 to permit relative sliding motion as the guide flanges 55 are adjusted towards or from each other. The outer, upper edges of both plates are flanged downwardly at right angles, as at 59 and 60, one overlapping the other, the inner flange 59 being provided with a longitudinal slot 61 in which operates the body of a screw 62 carried by the flange 60 and clamped by a nut 63 when the chute is properly adjusted. Rigidly secured to the under surface of each plate 53 and 54 are flat spring loops 64 to easily engage over the support bar 45 when turned in one direction and be held firmly thereon when turned in an opposite direction, due to contact of the projecting lugs 56 against the edge of the non-rotatable guides 47, this construction being best seen in Figure 5, this view clearly showing that when the chute 52 is rocked forward on the bar to clear the lugs 56 from the guides 47 and bring the arms of the loops 64 parallel with the flat face 46 of the bar, the chute may be raised bodily off the bar and out of the machine.

A knife 65 is supported between the plates 13 of the platen-displacing frame, adjacent the face of the platen 10, usually in such manner that it may be swung limitedly upward or downward. In order to avoid the necessity of such movement of the knife, which is occasioned by the difficulty in inserting a sheet of paper around the platen from the rear, there is provided two or more paper-fingers 66 curved to suit the platen, 70 the ends of the paper-fingers extending over the paper-deflector 42 at their lower extremity and their opposite ends bent re-entrantly upon themselves as at 67, providing a loop 68 shaped to snugly engage over the blade 75 of the knife 65 and which may be readily moved therewith into any desired position by a knob 69 fixed in the outer element of the loop, the knob also assisting in placing the finger on the knife and in removing it 80 therefrom, this being conveniently accomplished as the knife extends beyond the platen as shown in Figure 1.

When the fingers 66 and chute 52 have been removed from the machine, the gage- 85

bar 32 may be restored to its seat below the paper-table 33 and clamped by the screw 70 as shown in Figure 3, these changes or substitutions requiring no appreciable time in their accomplishment, but being effective in converting the machine to whichever purpose may be required of it.

Variations may be resorted to within the scope of the invention, and portions of the 10 improvements may be used without others.

Having thus described my invention, I claim:

1. In a typewriting machine having a carriage, a platen-displacing frame pivoted 15 on said carriage to swing upwardly and to the front, a platen revoluble in the frame, a knife mounted in the frame to swing adjacent the full length of the platen, and one or more paper-fingers adjustably engageable 20 with the knife to guide a work-sheet around the platen free from confliction with the knife.

2. In a typewriting machine having a carriage, a platen-displacing frame pivoted 25 on said carriage to swing upwardly and to the front, a platen revoluble in the frame, a knife mounted in the frame to swing adjacent the full length of the platen, and one or more bowed flat spring fingers to engage 30 the knife at any point along its length, said fingers extending partially around the platen and spaced therefrom.

3. In a typewriting machine, the combination with a cylindrical platen and a knife 35 disposed longitudinally adjacent the front thereof, of bowed spring fingers having re-entrantly turned loops to snugly engage the blade of the knife, the bowed portions of said fingers extending below and contiguous 40 to the platen, and knobs fixed in the outer elements of the loops by which the fingers may be adjusted on said knife.

4. In a typewriting machine having continuous billing mechanism applied thereto, 45 a platen, a platen-displacing frame to support the platen in normal or abnormal positions, a support-bar fixed on the machine at the rear of said frame, guides slideable on said bar to adjust the lateral edges of work-sheets, said guides being non-rotatable, and a paper-chute adjustable on said bar.

5. In a typewriting machine having continuous billing mechanism applied thereto, 55 a platen, a platen-displacing frame to support the platen in normal or abnormal positions, a support-bar fixed on the machine at the rear of said frame parallel with the platen, said bar having a non-cylindrical cross-section, guides adjustable lengthwise of 60 said bar, a sectional paper-chute carried by said bar telescopically adjustable on the bar, and work-sheet gages at the side edges of said chute.

6. In a typewriting machine having continuous billing mechanism applied thereto, 65

a platen, a platen-displacing frame to support the platen in normal or abnormal positions, a paper-deflector below the platen, a support-bar fixed on the machine at the rear of said frame parallel with the platen, said bar having a non-cylindrical cross section, guides adjustable lengthwise on said bar, and a paper-chute adjustable for width and also adjustable on said bar, the outer elements of the chute having raised lateral 75 gages.

7. In a typewriting machine having continuous billing mechanism applied thereto, 80 a platen, a platen-displacing frame to support the platen in normal or abnormal positions, a paper-deflector below the platen, a paper-apron above the platen, a support-bar fixed on the machine at the rear of said frame parallel with the platen, said bar having a non-cylindrical cross section, paper- 85 guides adjustable lengthwise on said bar, a paper-chute composed of two relatively adjustable sections, each having raised gages at their outer edges, means for guiding the sections during their relative movement, and 90 spring clips on each section engageable with said bar.

8. In a typewriting machine having continuous billing mechanism applied thereto, 95 a platen, a platen-displacing frame to support the platen in normal or abnormal positions, a support-bar fixed on the machine at the rear of said frame parallel with the platen, said bar having a flattened side, paper-guides adjustable lengthwise on said 100 bar, a paper-chute composed of two relatively adjustable sections, each having up-turned right angular flanges constituting gages, clips on each section engageable with said bar, and lugs extending outward from 105 the flanges to contact with the edges of the guides whereby the chute is maintained in position on the bar against rotation.

9. In a typewriting machine having continuous billing mechanism applied thereto, 110 a platen, a platen-displacing frame to support the platen in normal or abnormal positions, a support-bar fixed on the machine at the rear of said frame parallel with the platen, said bar having a non-cylindrical 115 cross section, guides adjustable lengthwise on said bar, a paper-chute composed of two relatively adjustable plates, each having up-turned right angular flanges on their outer side edges and downwardly-turned angular flanges on their top edges, the plates being arranged in overlapping relation, the lower plate having an elongated slot adjacent its bottom edge and a correspondingly elongated slot in its top flange, a headed pin 120 fixed in the upper plate to co-operate with the first-named slot, a screw fixed in the outer top flange to co-operate in the slot of the underlying flange, a nut to tighten 125 said screw holding the plates in adjustment, 130

and means on the lower surface of each plate to slidably engage on the support-bar.

10. In a typewriting machine having continuous billing mechanism applied thereto, a platen, a platen-displacing frame to support the platen in normal or abnormal positions, a support-bar fixed on the machine at the rear of said frame parallel with the platen, said bar having a non-cylindrical cross section, a paper-chute composed of two relatively adjustable plates, each having upturned right angular flanges on their outer side edges and downwardly-turned angular flanges on their top edges, the plates being arranged in overlapping relation, the lower plate having an elongated slot adjacent its bottom edge and a correspondingly elongated slot in its top flange, a headed pin fixed in the upper plate to co-operate with the first-named slot, a screw fixed in the outer top flange to co-operate in the slot of the underlying flange, a nut to tighten said screw holding the plates in adjustment, clips on each plate engageable on said bar, guides adjustable on the bar, means co-operative between said guides and bar to maintain the guides erect, and lateral projections on the sides of the upturned flanges to contact with the edges of said guides whereby the chute is held from tilting rearwardly and permitted to tilt towards the front.
11. In a typewriting machine having continuous billing mechanism applied thereto, a platen, a platen-displacing frame to support the platen in normal or abnormal positions, a paper-deflector below the platen, a knife extending lengthwise in front of the platen, a support-bar fixed on the machine at the rear of said frame, side guides slidable on said bar to adjust the edges of work-sheets, a paper-chute on said bar, said chute being composed of telescopic sections, means for securing said sections when in

adjustment, means for maintaining said chute normally tangent to the platen, paper-fingers engageable with the knife to extend below the platen, and means carried by said fingers by which they may be adjusted.

12. In a typewriting machine having continuous billing mechanism applied thereto, a platen, a platen-displacing frame to support the platen in normal or abnormal positions, a paper-deflector below the platen, a knife extending lengthwise in front of the platen, a support-bar fixed on the rear of said frame, side guides slidable on said bar to adjust the edges of work-sheets, a paper-chute on said bar, said chute being composed of telescopic sections, means for securing said sections when adjusted, means for maintaining said chute in position to deliver the work-sheets to said paper-deflector, and paper-fingers adjustably engaged with said knife to receive the work-sheets from the paper-deflector, said paper-fingers avoiding interference of the work-sheets with the knife.

13. In a typewriting machine having continuous billing mechanism applied thereto, a platen, a platen-displacing frame to support the platen in normal or abnormal positions, a paper-deflector below the platen, a knife extending lengthwise in front of the platen, a support-bar fixed on the rear of said frame, side guides slidable on said bar to adjust the edges of work-sheets, a paper-chute on said bar, said chute being composed of telescopic sections, means for securing said sections when adjusted, means for maintaining said chute in position to deliver the work-sheets to said paper-deflector, paper-fingers adjustably engaging said knife to receive the work-sheets from the paper-deflector, and a paper-apron over the platen, to which the work-sheets are delivered by said paper-fingers.

GEORGE A. GREENWOOD.
